UNITED STATES PATENT OFFICE.

MANSFIELD C. CRAWLEY, OF SAN FRANCISCO, CALIFORNIA, ASSIGNOR TO ADDOGRAPH COMPANY, A CORPORATION OF CALIFORNIA.

TYPE-WRITER.

1,077,675.

Specification of Letters Patent.

Patented Nov. 4, 1913.

Application filed December 21, 1909. Serial No. 534,284.

To all whom it may concern:

Be it known that I, MANSFIELD C. CRAWLEY, citizen of the United States, residing in the city and county of San Francisco and State of California, have invented new and useful Improvements in Type-Writers, of which the following is a specification.

This invention relates to typewriters, and pertains especially to electrically-operated typewriters.

The object of my invention is to provide a durable, reliable electrically-operated, visible typewriting machine which will particularly combine certain simple mechanical and electrical features whereby the type-bars of the typewriter may be actuated in proper sequence and with great rapidity by a very light pressure upon the keys; and which will provide a manually-operated selective mechanism in combination with a single electrical power unit or actuator to actuate the type-bars, the type-bars being electrically operated after the manual selection or preparation has been made.

It includes other objects and advantages which will be apparent hereinafter.

The invention consists of the parts and the construction and combination of parts as hereinafter more fully described and claimed, having reference to the accompanying drawings, in which—

Figure 1 is a plan of the machine. Fig. 2 is a central vertical section. Fig. 3 is a front view omitting portion of the key elements. Fig. 4 is a perspective of the type-bar action. Fig. 5 is a perspective view of the type-bar and ribbon guides. Fig. 6 shows the coupler in tripped position.

In a machine which I have built embodying the invention, I employ a main supporting frame A of suitable design and proportion, in the forward extension of which are character indicating keys 2 secured to the outer end of levers 3, which latter are fulcrumed upon a transverse bar 4. There are as many key-levers 3 provided as are necessary to select any of the type-bars 5 which are journaled at 5' upon adjustable hangers 6 detachably secured to the segment 7, Figs. 2 and 4.

It is understood that a description of one key and its connecting parts will apply to all the keys and characters of the machine.

An important feature of this invention is

the provision of selecting mechanism by means of which the initial selection or preparation of a certain type-bar is performed. As here shown, 9 is a bar pivoted to a lever 3 at 8 and working through a guide ring 10. The upper beveled end of each bar 9 is adapted, when a key 2 is slightly depressed, to engage a coupler 11 pivoted at 12 to the inner end of a type-bar 5, and sustained at its outer free end by a spring 13, or its equivalent, and when the coupler 11 is uplifted by the bar 9 it is carried into operative position with a push bar 16, to be hereinafter described. Each bar 9 with its lever 3 is normally held in the lowermost position by a spring 14 which retains the bar 9 seated in the guide ring 10. Each coupler 11 being pivoted at 12 to its respective type-bar 5 will, when raised by its bar 9, present a concaved face 15 to the semicircular push-bar 16, Figs. 1 and 3, which latter is secured to the forward ends of the slide rods 17, and adapted when slid forward to engage the coupler 11 and thereby swing the type-bar 5 upwardly about its pivot 5' to cause the type-bar to print. The moment the type has struck the platen 33', the bar 5 is quickly retracted by the coupler sustaining spring 13.

18 represents an electro-magnet for operating the push bar 16, and 17 are rods which carry bar 16 and connect to the armature 19 of the magnet 18. Rods 17 are slideable through a brace 20 which carries the magnet. The magnet 18 is connected to batteries 21 by suitable wires 22-23 through which a current may be sent to energize the magnet when the normally open contacts 24 of the circuit wires are closed.

The closing of the circuit is accomplished from the key-lever 3 and subsequent to the positioning of the coupler 11 in the path of the push bar 16 through the instrumentality of a pivoted foot-piece 25 loosely fulcrumed on the end of each lever 3 and which is adapted to engage a cross-bar 26, Figs. 2 and 3, of a frame 27 pivoted at 28.

Upon the free, lower end of the pivoted frame 27 is an adjustable screw 29 adapted when the lever 3 is actuated to strike the lower contact 24 and close the circuit, thereby energizing the magnet 18 and impelling the push bar 16 against the face 15 of the coupler 11 which has been elevated by the selector bar 9 at the initial movement of the

key 2; the operation of the push bar 16 causes the type-face on the particular type-bar 5 to print.

The type ribbon is moved into and out of operative position between the uplifted type and the platen each time a key is struck, by the following means: When the push bar 16 hits the coupler 11 it swings the type-bar 5 to the printing position and simultaneously 10 oscillates a bell-crank 30 fulcrumed at 31 on the end of a link 32 which is mounted in suitable manner on the brace 20. Referring to Figs. 2 and 5, the bell-crank 30 is illustrated as having one arm connected with a 15 ribbon guide 33, which latter is slidably guided by a type-bar guide 34 secured to a web 35 of the sector 7, and by this means the ribbon (not shown) is elevated just before the type-bar strikes the platen 33', 20 and is lowered as the push bar 16 is retracted to its idle or rear position by appropriate means, as the tension springs 36, Fig. 1; these springs having one end connected to the slide rods 17 and the other end 25 to posts 37 on brace 20. Thus it is seen that the keys 2 are manually operated and the type are electrically operated; and since the burden of manually impelling the type-bar 5 is avoided, and the resistance and 30 weight thereof are entirely removed from any connection with the key-lever, this lever is very easily depressed; and as the peculiar design of elements embodied in my invention requires a very short stroke of the key, 35 the expert operator may attain, for these reasons, a maximum speed and with a minimum physical exertion.

In order to insure a breaking of the magnet-energizing circuit 22-23 by means in 40 dependent of the lever 3 so that a series of keys 2 may be successively and rapidly depressed, and even while pressure remains on more than one key, the slide rods 17 carrying the push bar 16 have fastened to them 45 depending arms 38, secured to the forward ends of which is a transversely extending plate or trip 39 of such length as to encounter, when carried forward by the rods 17, any of the several pivoted foot-pieces 25, 50 thereby unlatching the previously actuated member 25 from the cross-bar 26, allowing frame 27 to fall under the action of gravity and spring 26', and consequently opening the circuit at switch 24 and deenergizing 55 magnet 18. This circuit breaking action, it will be seen, occurs immediately the type has struck the platen, and regardless as to whether the operator has released his pressure on the key 2 or not. Preferably the 60 member 25 is so balanced that after it has been unlatched it tilts back so as to clear the bar 26 as frame 27 falls, Fig. 4; the member 25 again assuming an upright position when it rests upon the bottom of the 65 frame A. Also, in order that the same cou-

pler 11 will not be hit when the push bar 16 moves forward again following the depression of another key, each coupler is adapted, after being struck by the push bar, to fly forward and upward as its type-bar 5 is carried upward to print, and when the circuit is broken, retracting the push bar, the type-bar 5, in falling back, carries the lug 11^a on the coupler forward of the end of the bar 9, provided the key to which this particular bar 9 is attached, is still depressed. This is shown graphically in Fig. 6. Unless there was some means for thus disconnecting the coupler from the push bar and taking it out of operative range of the 80 push bar, confusion would result by the operation of more than one type-bar. By the provision here made, the type-bars are allowed to fall back after each imprint far enough so as to be out of interference one 85 with the other in the rapid successive action of the type-bars. Of course, the moment the pressure on the key is released, the bar 9 is pulled down so as to come beneath the lug 11^a again, as shown in Fig. 2, 90 ready for the next operation of this key.

The operation of the machine is as follows: A depression of a key 2 rocks its lever 3 and carries the bar 9 up into engagement with and lifts a type-bar coupler 11 into 95 alinement with the push bar 16. The depression of key 2 also lifts its foot-piece 25, which latter in turn hits cross-bar 26, rocks frame 27, and closes the circuit through wires 22-23 at 24, thereby energizing magnet 18 which attracts its armature and moves the universal push bar 16 forward. The coupler 11 is elevated in time to be in proper position to be hit by the actuator 16 which is impelled at the instant the circuit 105 is closed, and the type on the type-bar 5 makes the desired imprint on the paper on the platen. Coincident, however, with the advance of the push bar 16, the ribbon guide 33 is elevated by the bell-crank 30 to printing position, and it is lowered in unison with the return of the push bar, thus rendering the printing visible. The instant the platen is struck by the type-bar, the trip 26 engages the foot-piece 25 and releases it 115 from bar 26, allowing frame 27 to fall, and breaking the circuit in contacts 24; and the push bar is returned to idle position by its springs 36, allowing the spring 43 to retract the coupler 11 and the type-bar 5.

In order to provide for any adjustment which may be necessary to compensate for the wear of the journal 5' of the type-bar 5, so that the type on the bar will always print in proper line, the rear end of the 125 hanger 6 is formed with a semicircular boss 6', Fig. 4, adapted to seat and rock in a corresponding groove on the under side of the sector 7. Passing through the hanger 6 is a draw-screw 130

40 adapted to hold the hanger; and reacting against this screw is an adjusting set-screw 41 threaded in the sector 7 and bearing loose on the hanger 6. By unscrewing the draw-screw 40 and running down screw 41, the hanger 6 swings away at its forward end, thereby lowering the pivot 5'; and vice versa, by unscrewing 41 in the sector 7 and screwing up screw 40, the pivot is raised.

10 An essential and important factor in the attainment of a high-speed, reliable and durable typewriting machine resides in requiring as little effort, mental and physical, of the operator as is possible, and yet provide a machine of such simple structure as to eliminate error, both of the operator and the operation.

In my machine the operator simply presses a key to close a circuit and the type-bar is operated electrically; the circuit being broken automatically and the type returned to initial position independent of the operator, and so quickly, that experience shows that the keys cannot be struck successively so fast as to cause an interference of one type-bar or type-face, with another. The keys do not have to be struck a blow; they may be pushed down ever so lightly. They do not have to be quickly released either; the retraction of the type-bar being accomplished automatically, as we have seen. All that is necessary is that two or more keys are not depressed simultaneously, and as long as characters do not have to be duplicated the several keys may be depressed successively and held down, yet each key will cause a perfect printing action to take place.

In the event wear occurs in the jaws 34' of the type-bar guide 34, the jaws are made slightly springy and are provided with a limiting set-screw 45 and a draw-screw 46, which latter tends to draw the jaws together. By this means the jaws 34' may be gradually adjusted to compensate for any wear either on the guide or on the type-bars.

The segmental guide 7 is important in that it consists of a segmental bar slotted so as to form guides and a lateral support for each one of the type-bars 5.

Having thus described my invention, what I claim and desire to secure by Letters Patent is—

1. In an electrical typewriter, the combination of a pivoted key bar, a sliding rod directly pivoted on and carried by the key bar, a push bar, a pivoted type bar, a coupler pivoted directly to the type bar and arranged in the path of the sliding rod, so that when the latter is reciprocated the coupler is positioned in the path of the push bar, and electrical means controlled by the key bar whereby on the depression of the key bar the push bar is operated to actuate the type bar.

65 2. In an electrical typewriter, the combination of a pivoted key bar, a sliding rod directly pivoted on and carried by the key bar, a push bar, a pivoted type bar, a coupler pivoted directly to the type bar and arranged in the path of the sliding rod, so that when the latter is reciprocated the coupler is positioned in the path of the push bar, electrical means controlled by the key bar whereby on the depression of the key bar the push bar is operated to actuate the type bar.

70 3. In an electrical typewriter, the combination of a pivoted key bar, a sliding rod directly pivoted on and carried by the key bar, a push bar, a pivoted type bar, a coupler pivoted directly to the type bar and arranged in the path of the sliding rod, so that when the latter is reciprocated the coupler is positioned in the path of the push bar, electrical means controlled by the key bar whereby on the depression of the key bar the push bar is operated to actuate the type bar, and means independent of the movement of the key bar for disrupting the electrical connections whereby the type bar may return to initial position, independent of the movement of the key bar.

75 3. In an electrical typewriter, the combination of a pivoted key bar, a sliding rod directly pivoted on and carried by the key bar, a push bar, a pivoted type bar, a coupler pivoted directly to the type bar and arranged in the path of the sliding rod, so that when the latter is reciprocated the coupler is positioned in the path of the push bar, electrical means controlled by the key bar whereby on the depression of the key bar the push bar is operated to actuate the type bar, and means operatively connected to the power bar for disrupting the electrical connections.

80 4. In a typewriting machine, the combination of a series of movable type-bars, a key for each type-bar, means including a single electrically operated actuator common to all the type-bars for operating any type-bar on the depression of a corresponding key, means controlled by said actuator for disconnecting the same from the control of the key after the type-bar has been moved to printing position, and independent of whether pressure on the key has been released or not, and a movable ribbon guide operated directly by said actuator.

85 5. In a typewriting machine, the combination of a pivoted type-bar, a coupler member carried thereby, an actuator bar, a key-lever, means on the key-lever for moving the coupler into operative position with respect to the actuator-bar, electrically controlled mechanism controlled by the key-lever for operating the actuator-bar, means operated by the actuator bar operating means for disconnecting the coupler, a platen, and a movable ribbon guide operative directly by the actuator bar which controls the key-bar.

90 6. In an electrical typewriter, the combination of a pivoted type-bar, a pivoted coupler thereon, a key-lever, an actuator, a ribbon guide actuated thereby, a circuit, a magnet in the circuit, means whereby on the energizing of the magnet the actuator is operated, a switch in the circuit, and means controlled by the key-lever for closing the switch, said means including a rocking frame pivotally mounted at its upper end and having its opposite end positioned near

said switch and provided with a contact, and a pivoted foot piece on the key-lever.

7. In an electrical typewriter, the combination of a pivoted type-bar, a pivoted coupler thereon, a key-lever, an actuator, a ribbon guide actuated thereby, a circuit, a magnet in the circuit, means whereby on the energizing of the magnet the actuator is operated, a switch in the circuit, means controlled by the key-lever for closing the switch, said means including a rocking frame pivotally mounted at its upper end and having its opposite end positioned near said switch and provided with a contact, and a pivoted foot piece on the key-lever, and means independent of the key-lever for opening the switch.

8. In an electrical typewriter, the combination of a pivoted type-bar, a pivoted coupler thereon, a key-lever, an actuator, a ribbon guide actuated thereby, a circuit, a magnet in the circuit, means whereby on the energizing of the magnet the actuator is operated, a switch in the circuit, and means controlled by the key-lever for closing the switch, said last-named means including a

pivoted switch closer, and a foot piece pivoted on the rear end of the key-lever having an upper portion engageable with said switch closer.

9. In an electrical typewriter, the combination of a pivoted type-bar, a pivoted coupler thereon, a key-lever, an actuator, a circuit, a magnet in the circuit, means whereby on the energizing of the magnet the actuator is operated, a switch in the circuit, means controlled by the key-lever for closing the switch, said last-named means including a pivoted switch closer, and a foot-piece pivoted on the rear end of the key-lever having an upper portion engageable with said switch closer, and means operative by the actuator for engaging the trip member to release it from said switch closer.

In testimony whereof I have hereunto set my hand in the presence of two subscribing witnesses.

MANSFIELD C. CRAWLEY.
